UNITED STATES PATENT OFFICE.

WILLIAM SIDNEY HOWARD DOODY, OF SYDNEY, NEW SOUTH WALES, AUSTRALIA.

SANDAL OR SLIPPER.

1,407,992.

Specification of Letters Patent. Patented Feb. 28, 1922.

Application filed October 22, 1920. Serial No. 418,844.

To all whom it may concern:

Be it known that WILLIAM SIDNEY HOWARD Doody, subject of the King of Great Britain and Ireland, residing at 80 Hunter Street, 5 Sydney, New South Wales, Australia, has invented certain new and useful Improvements in Sandals or Slippers, of which the following is a specification.

This invention relates to sandals or slippers. Its object is to provide a sandal or slipper which may be constructed cheaply and is provided with fastening straps adjustable in relation to the foot of the wearer.

Sandals or slippers in accordance with the invention comprises a sole; a toe strap secured at one end to the sole; a pair of instep straps secured at one of their ends to opposite sides of the shank of the sole; an elongated tie link of metal or a tie link of elastic material to which the other ends of the toe and instep straps are attached; and a pair of straps for the sides of the foot, one of the respective ends of which is secured to opposite sides of the forepart of the sole, and the other ends are attached to the tie link. A strap may also be provided at the heel of the sandal or slipper, adapted to be connected by an elastic or other cord to the instep straps.

The face of the sole is constructed of a strip of leather, rubber or canvas which is preferably reinforced by a backing strip or strips of dried tea or ti tree bark. Said bark is obtainable from the paper-bark tree or so-called tea or ti tree (*Melaleuca Leucadendron*, variety *Albida*). The reinforcing material is covered by a strip of cotton, linen, canvas or other suitable fabric. The sole reinforcing material and covering therefor are joined to each other at their edges by stitching or otherwise.

If the sandal or slipper is to be waterproofed, the materials of which it is constructed are treated to render them waterproof.

In the accompanying drawing, Fig. 1 is a perspective view of the sandal or slipper; Fig. 2 a detail view showing a fastening link for the front straps of the sandal or slipper, 50 the link being positioned to adapt the sandal or slipper for wear by a person having feet of broad width; Fig. 3 a detail view similar to Fig. 2 but showing the fastening link positioned to adapt the sandal or slipper for wear by a person having feet of

narrow width; Fig. 4 a longitudinal section of the sandal or slipper; Fig. 5 a broken perspective view of the front portion of a sandal or slipper of similar construction to that shown in Fig. 1 but with an elastic ring 60 fastening link; and Fig. 6 is a detail plan view of the ring link fastening shown in Fig. 5.

The sole 1 of the slipper or sandal consists of a strip of leather, rubber, or canvas, 65 backed with a reinforcing strip of ti or tea tree bark 2 or other suitable material; the bark is covered by a strip of cotton, linen, or canvas fabric 3. At the forepart of the sandal is a toe strap 4 and side straps 5 and 6, and extending from the shank of the sandal are the instep straps 7 and 8. The rear of the sandal carries the heel strap 9. One end of each said straps is secured between the sole 1 of the sandal and the reinforcing strip 2 therefor. The sole 1 and the reinforcing and cover strips 2 and 3 are preferably sewn together at their edges by stitching such as 10. The respective straps may be of leather or canvas.

Each of the straps is formed with a loop 11 at its free end. These loops may be formed by folding the respective free ends of the straps and uniting the separate over-folded ends by an eyelet 12. The looped 85 ends of the straps 4, 5, 6, 7 and 8 are coupled to a metal link 13 or to a ring of rubber or similar elastic material 14. If a metal coupling link is utilized it may be of elliptic or spheroid or other suitable shape; the link 90 must, however, be elongated in one direction to permit the straps secured thereto to be adjusted to the size of the feet of the wearer. The links 13 and 14 are capable of being turned in the loops 11 of the straps 4 to 8. 95

When the link 13 is turned in a direction in which its longer axis is lying transversely of the sandal or slipper as shown in Figs. 1 and 2, the side straps 5 and 6 are loosened and the instep straps 7 and 8 are tightened, 100 whereas when the link is lying in the opposite direction as shown in Fig. 3 the straps 5 and 6 are tightened and the instep straps 7 and 8 are loosened. The adjustment of the respective pair straps 5 and 6 and 7 and 8 105 by means of the link 13 enables the sandal or slipper to be fitted to feet of varying width. Similarly, the elastic ring link 14 is adapted to allow the straps 5 and 6 and 7 and 8 to be adjusted to permit the sandal or 110

slipper to be fitted to feet of varying width. The metal of the link 13 is preferably circular in cross section though it may be made to any other preferred section.

5 A cord of elastic material 15 having its free ends joined is threaded through the looped end of the heel strap 9 and eyelet holes 16 in the instep straps 7 and 8. Such cord extends around the ankles of the wearer of the sandal or slipper.

To render the component parts of the sandal or slipper waterproof, the reinforcing strips of tea or ti tree bark are treated with an oily or fatty substance. Such substance may be applied to the bark either by rubbing it into same or by immersing the bark in a bath of the substance. The respective straps 4 to 9 are also similarly treated with an oily or fatty substance but preferably by immersing them in a bath of the substance. If the sole of the sandal or slipper consists of a strip of leather or canvas which is backed by a strip or strips of tea or ti tree bark, the face thereof in contact with the bark is also coated with an oily or fatty substance. The sole may, however, be constructed of a strip of rubber in which event it is unnecessary to treat it with the oily or fatty substance. The cover strip of 30 cotton, linen or canvas 3 is also impregnated with an oily or fatty substance. Said oily or fatty substance must be of such character that it will not impart any disagreeable odor to the parts of the sandal or slipper treated therewith. Paraffin wax has been found effective for the purpose. When the cover strip 3 has been impregnated with the substance it may be placed on the strip of bark and caused to adhere thereto by pressure applied either by means of rollers or otherwise.

After the straps of the sandal or slipper have been treated with the oily or fatty substance their outer faces may be coated with thin varnish or like material. Similarly the

outer face of the strip 3 may also be coated with varnish or like material.

In the appended claims the reference to "forepart straps" is to be understood to refer to the side straps 5 and 6.

What I claim as my invention and desire to secure by Letters Patent is:—

1. A sandal or slipper comprising a sole secured by stitching to a backing strip consisting of ti tree bark covered with cloth 55 fabric, a toe strap, forepart straps at each side of the sole, instep straps extending from each side of the shank of the sole, each of said straps being secured at one end between said sole and its backing strip and 60 having a loop on its free end, and a metal coupling link elongated in one direction threaded through the loops of said strap and adjustable therein to permit loosening or tightening of said forepart or instep straps 65 on the foot of the wearer of said sandal or slipper.

2. A sandal or slipper comprising a sole secured by stitching to a backing strip consisting of ti tree bark covered with cloth 70 fabric; a toe strap; forepart straps; instep straps extending from each side of the shank of the sole; a heel strap at the rear of the sole; each of said straps being secured at one end between said sole and backing strip 75 and carrying a loop at its free end; a coupling link threaded through the loops of said toe, forepart, and instep straps said link being so shaped that by changing its position an adjustment of said straps may be 80 secured; said straps, sole, and covered backing strip being treated with an oleaginous substance to render them waterproof; and an elastic cord secured respectively to said heel strap and instep straps adapted to fit 85 around the ankles of the wearer of said sandal or slipper.

In testimony whereof I have affixed my signature.

WILLIAM SIDNEY HOWARD DOODY.
